UNITED STATES PATENT OFFICE.

HENRY G. FRENCH, OF SCHENECTADY, NEW YORK, ASSIGNOR TO GENERAL ELECTRIC COMPANY, A CORPORATION OF NEW YORK.

PROTECTIVE DEVICE.

1,397,276.

Specification of Letters Patent.

Patented Nov. 15, 1921.

Application filed October 24, 1919. Serial No. 383,920.

To all whom it may concern:

Be it known that I, HENRY G. FRENCH, a citizen of the United States, residing at Schenectady, county of Schenectady, State 5 of New York, have invented certain new and useful Improvements in Protective Devices, of which the following is a specification.

My invention relates to protective devices, 10 particularly to relays and has for its object to provide a relay of the induction type which will be positively set into operation upon the occurrence of any predetermined abnormal condition, which will positively and 15 definitely move to complete its path of movement, which is quickly reset to its initial position and which consists of other improvements which will be set forth more in detail hereinafter.

20 The novel features which I believe to be characteristic of my invention will be definitely indicated in the claims appended hereto while the features of construction and mode of operation will be understood by 25 reference to the following description taken in connection with the accompanying drawing in which:

Figure 1 shows, in perspective, a relay embodying the principle of my invention and 30 Fig. 2 shows in outline, the wiring diagram for my device.

My novel and improved relay comprises a rotatable armature 1, movable with a time delay by a permanent magnet 2 and controlled by a torque producing device comprising a motor element 3, and a counter torque or restraining element 4. The restraining element 4 comprises, preferably a spring operatively related to a contact carrying shaft 5. This shaft carries a movable contact member 6 which is adapted to be moved into and out of engagement with co-operating fixed contacts 7 to close an auxiliary tripping circuit, as best shown in Fig. 2. 40 The armature 1 is carried by a shaft 8 which is movable into and out of driving relation with shaft 5 by means of a clutch device which is of the electromagnetic type. This clutch device consists of friction engaging disks or plates 9 carried by shafts 5 and 8 and biased into driving engagement by a spring 10. The disks 9 of the clutch device are controlled by an electromagnetic element comprising a magnetic member 11 having 45 pole pieces 12 on opposite sides of shaft 8

and in magnetic relation to the lower disk 9. The member 11 also carries two windings 13 and 14, one adjacent each pole piece 12. When either coil is energized, the flux across pole pieces 12 acts upon the lower disk 9 60 attracting it as an armature against the action of spring 10 and thereby moving it out of engagement with the upper disk 9. The clutch is then disengaged and the shaft 5 with contact 6 is then movable independent 65 of the armature 1. The coils 13 and 14 of the clutch control device are operative in response to different conditions, one coil being energized when the contacts 6 and 7 are brought into engagement, while the other 70 coil is energized in response to the falling off of the abnormal condition before the relay contacts engage, as will be described more in detail hereinafter.

The motor element 3 comprises a main 75 winding 15 connected through a transformer 16 to the circuit 17 to be protected and a compensating means including an auxiliary winding 18. The effect of the auxiliary winding 18 is controlled by an electromagnetic device 19. This device comprises a magnetic circuit member 20 carrying winding 21, as best shown in Fig. 2, and provided with a variable air gap controlled by a movable plunger 22. The position of plunger 22 80 may be varied and the air gap controlled by an adjusting means 23. As best shown in Fig. 2, the compensating or auxiliary winding 18 is in a normally closed series circuit with the winding 21 of electromagnetic device 19, the winding 18 being in inductive 85 relation with the main winding 15 of the motor element 3. Normally clutch 9 is in engagement and the effect of the restraining or counter torque element overcomes the 90 effect of the torque or motor element 3.

As the load increases in the circuit 17 more current passes through winding 15 of the motor element 3 and more current is induced in the auxiliary winding 18 which 100 causes a corresponding increase in current in winding 21 of electromagnetic device 19. Upon the passage of a predetermined current in circuit 17, the current flowing in winding 21 is sufficient to pick up plunger 22 105 and close the air gap in the magnetic circuit member 20. The closure of this air gap increases the inductance of the winding 21 which acts to decrease the current in auxiliary winding 18 of the motor element. The 110

phase relations of the flux produced by windings 15 and 18 of the motor element 3 are so shifted in response to operation of electromagnetic device 19 that an increase of 5 torque is produced by the motor element 3 on the rotatable armature 1. This increase in driving torque is sufficient to overcome the counter torque exerted by the restraining or counter torque element 4 and move 10 the armature 1 in contact controlling direction. The increase in counter torque produced by the spring 4 as the armature 1 is rotated, is compensated for, by the increase in torque produced by the effect of auxiliary 15 winding 18 so that the armature is carried positively into contact closing position bringing the contacts 6 and 7 into engagement. The closure of these contacts energizes the circuit of trip coil 24 to open switch 20 25 controlling the circuit 17 to be protected.

The engagement of contacts 6 and 7 to energize trip coil 24, also energizes the coil 14 of the clutch control device, which is in series, as best shown in Fig. 2. This coil 14 25 through its magnetic member 11 attracts the lower disk 9 of the clutch and moves the disk 9 out of engagement with its coöperating disk against the action of spring 10. This disengagement of disks 9 moves the shafts 30 5 and 8 out of driving engagement and removes the effect of the restraining element or spring 8 upon the armature 1. The spring 4 thereupon exerts its effect to return shaft 5 and the movable contact 6 quickly to 35 initial position against stop 26 independent of armature 1 thereby quickly resetting the relay while the armature remains undisturbed. The stop 26 is carried on an adjustable arm 27 by means of which the position 40 of the stop can be varied to vary the path of movement of contact 6 and hence the time element of the relay. The resetting of the contact 6 breaks the circuit of coil 14 and disks 9 of the clutch, and returns it in 45 position for the next operation.

It often happens that the overload necessary to start the armature into operation falls off before the relay has had time to operate, that is, before the armature has 50 completed its path of movement. Under such circumstances, it is essential to return the relay to its initial position quickly without the effect of floating. To meet this condition, I have provided a control device 55 operative to energize the other coil 13 of the clutch control element to quickly reset the contacts as has been described. This device comprises a permanent magnet 28 between the poles of which the armature 1 is 60 rotatable. The magnet 28 is pivotally mounted upon a support 29 and carries a movable arm 30 having a contact member 31. Coöperating with the movable contact 31 is a fixed contact member 32 which con-

tacts control the circuit of coil 13 as shown 65 in Fig. 2. The magnet 28 and contact arm 30 are biased to bring contacts 31 and 32 into engagement by any suitable means such as spring 33. Also associated with the end 70 of arm 30 is a double lever device controlled by the electromagnet 19. This device consists of levers 34 and 35 secured to opposite ends of a shaft 36 and movable as a unit. Lever 34 has a lug 37 extending into the path of movement of arm 30 and lever 35 75 has a lug 38 extending into the path of movement of plunger 22 of electromagnet 19. Normally plunger 22 of electromagnetic device 19 engages lug 38 of lever 35 and through lever 34, its lug 37 engages the end 80 of arm 30 and holds the contacts 31 and 32 out of engagement. When plunger 22 picks up and the armature 1 starts to rotate the restraint of lever 34 is removed. The effect 85 of induction, however, moves the magnet 28 on its pivot in a direction such that the arm 30 still holds contacts 31 and 32 out of engagement during the movement of the armature 1 in contact closing direction. If the overload falls off, however, before the armature 1 has brought the relay contacts 6 and 7 into engagement, thereby causing the armature to be retarded in its movement, the pull exerted by spring 33 moves the magnet 28 on its pivot and brings arm 30 90 into a position where contacts 31 and 32 engage, as can best be seen in Fig. 2. The engagement of contacts 31 and 32 closes a circuit to energize clutch winding 13 which thereupon acts to separate the disks 9 and, 95 as before explained, permits the contacts 6 to be immediately reset independent of the armature. 100

What I claim as new and desire to secure by letters Patent of the United States, is:— 105

1. In a relay device, the combination with a rotatable armature, relatively coöperating fixed and movable contacts operatively related thereto, a torque element for rotating said armature to contact controlling position, a restraining element opposing said torque element, and means operative in response to the engagement of said contacts whereby said restraining element operates to return said movable contact to initial 110 position independent of said armature. 115

2. In a relay device, the combination with a rotatable armature, fixed contacts, a coöperating contact movable by the rotation of said armature into engagement with said 120 fixed contacts, a torque element for rotating said armature, and a restraining element coöperating with said armature to oppose the action of said torque element, and means responsive to predetermined electrical conditions for causing said coöperating contact to be moved in contact engaging direction 125 in response to said armature and in the op-

posite direction in response to said restraining element, independent of said armature.

3. In a relay device, the combination with fixed contacts, and a movable contact member, of a rotatable armature, a torque element for rotating said armature, and means for causing said armature to carry said movable contact into engagement with said fixed contacts and for returning said contact to its initial position independent of said armature.

4. A relay comprising relatively movable coöperating contacts, a rotatable armature member, a torque member for rotating said armature, means normally exerting a counter torque on said armature, means for disconnecting said counter torque means from said armature in response to predetermined electrical conditions, a fixed contact, and a movable contact carried into engagement with said fixed contact by the rotation of said armature, and returned to initial position by said counter torque means.

5. In a relay device, the combination with a rotatable armature, a torque element for rotating said armature in one direction, a counter torque element acting to restrain the rotation of said armature and adapted to be disconnected therefrom, means for disconnecting said counter torque element, fixed contacts, and a coöperating contact controlled by said counter torque element.

6. In a relay device, the combination with a rotatable armature, a torque element for rotating said armature, relatively movable coöperating contacts adapted to be brought into engagement by the rotation of said armature, and means for resetting said contacts independent of said armature.

40 7. In a relay device, the combination with a rotatable armature, a shaft therefor, a co-operating shaft, a movable contact carried by said coöperating shaft, a fixed contact with which said movable contact is engageable, a torque element for rotating said armature, means for causing a rotation of said coöperating shaft in response to rotation of said armature shaft to carry said movable contact into engagement with said fixed contact, and means for rotating said coöperating shaft in the opposite direction independent of said armature shaft to return said movable contact to its initial position.

55 8. In a relay device, the combination with a rotatable armature, a torque element operative in response to current above a predetermined amount for rotating said armature, a fixed contact, a movable contact carried into engagement with said fixed contact in response to rotation of said armature, and means for quickly returning said movable contact to its initial position independent of said armature in response to the engagement of said contacts and at any point in

the path of movement of said movable contact if the current falls below said predetermined amount.

9. In a relay device, the combination with a rotatable armature, means restraining said armature against movement, contacts controlled by said armature, means for overcoming said restraining means and rotating said armature in contact controlling direction in response to abnormal conditions above a predetermined amount, and means operative in response to the engagement of said contacts and in response to the falling of said abnormal conditions below said predetermined amount for quickly resetting said contacts in their initial position.

10. In a relay device, the combination with a fixed contact, a movable contact engageable therewith and biased to initial position, a rotatable armature, means for rotating said armature in response to current in excess of a predetermined amount, means normally operative to cause said movable contact to be moved in response to rotation of said armature in a direction to engage said fixed contact but operative in response to the engagement of said contacts and to the falling of the current below said predetermined amount to enable said movable contact to quickly return under its bias to initial position independent of said armature.

11. In a relay device, the combination with a rotatable armature, contacts controlled thereby, a torque element for moving said armature into contact controlling position, a counter torque element normally predominating but overcome by said torque element in response to abnormal conditions above a predetermined amount, means for compensating for the increase in effect of said counter torque element as said armature is rotated in response to said torque element, and means for quickly effecting the resetting of said contacts to initial position independent of said armature in response to the engagement of said engagement and the falling of conditions below said predetermined amount.

12. In a relay device, the combination with a rotatable armature, a fixed contact, an independently movable contact adapted to be moved thereby into engagement with said predetermined contact, a torque element for rotating said armature in contact engaging direction, biasing means for holding said movable contact in initial position, and means for rendering said movable contact operative in response to rotation of said armature to move into engagement with said fixed contact, and means for rendering said first mentioned means inoperative in response to the engagement of said contacts.

13. In a relay device, the combination with a rotatable armature of a torque element tending to move said armature in one direc-

tion, a counter torque element exerting a restraining effect on said armature, a fixed contact, and a coöperating contact movable into engagement with said fixed contact in response to said torque element and to initial position independent of said armature in response to said counter torque element.

14. In a relay device, the combination with 10 relatively movable coöperating contacts, of actuating means for moving said contacts into engagement in response to abnormal conditions above a predetermined amount, and means for quickly returning said contacts from engaging to initial position and 15 from any intermediate point in response to the falling of said abnormal conditions below said predetermined amount independent of said actuating means.

15. In a relay device, the combination with 20 a rotatable armature, a torque element for rotating said armature in one direction, an independent spring element adapted to be connected to said armature to oppose the action of said torque element, a movable contact carried by said spring element, a coöperating fixed contact, a clutch device normally acting to connect said spring element 25

to said armature whereby said movable contact is carried into engaging position in response to the rotation of said armature under the increasing restraining force exerted by said spring, and means operative in response to the engagement of said contacts for disengaging said clutch device whereby the tension exerted by said spring returns 35 said movable contact quickly to initial position independent of said armature.

16. In a relay device, the combination with 40 a movable contact, a coöperating fixed contact, a spring acting to hold said movable contact in initial position, an actuating means, and means for connecting said movable contact to said actuating means to cause its movement thereby into engagement with said fixed contact against the action exerted 45 by said spring, and means responsive to the engagement of said contacts for disconnecting said movable contact from said actuating means whereby it is returned to initial position independent of said armature by the 50 tension exerted in said spring.

In witness whereof, I have hereunto set my hand this 23rd day of October, 1919.

HENRY G. FRENCH.
